OF TOLEDO, OHIO, A CORPORATION OF OHIO

PROCESS AND APPARATUS FOR ANNEALING GLASS

Application filed January 2, 1926. Serial No. 78,772.

The present invention relates to an improved process and apparatus for annealing sheet glass.

An important object of the invention is to provide an annealing oven or leer with means whereby a less turbulent atmosphere may be maintained within the oven.

Another object of the invention is to create within a confined heated atmosphere a medium having a sustained temperature condition which gradually decreases throughout its length, and which is substantially uniform throughout its width.

A further object of the invention is to create within an annealing oven and around the glass passing therethrough a condition which is capable of protecting the glass from intercourse with elements having objectionable temperatures.

Other objects and advantages of the invention will become apparent during the course of the following description.

In the drawings whereby like numerals are employed to designate like parts throughout the same,

Fig. 1 is a longitudinal sectional elevation of the improved annealing oven,

Fig. 2 is a transverse section through a hot portion of the oven taken substantially on line 2—2 in Fig. 1,

Fig. 3 is a fragmentary transverse section through a cooler portion of the oven taken substantially on line 3—3 of Fig. 1.

Referring to the drawings in detail, the numeral 4 refers to a chamber in which the sheet of glass 5 is continuously drawn and flattened in a manner more fully disclosed in a patent to Colburn 1,248,809, granted Dec. 4, 1917.

In front of and attached to the chamber 4 in horizontal alignment with the sheet as it passes therefrom is an oven or leer 6 of suitable size for annealing the sheet. The sheet 5 is preferably advanced through the leer 6 upon and by a plurality of driven rolls 7.

There are openings 8 provided in the side walls of the leer for either removing or replacing the rolls 7. Unless these openings are suitably closed or sealed, unequal heat losses will result therefrom which may prove un-

desirable toward proper annealing of the sheet. By inserting plugs 9 of suitable insulation within the openings 8 these heat losses will be somewhat neutralized.

The leer is preferably heated by means of burners 10 suitably spaced longitudinally thereof. As set forth in my copending application, Serial No. 75,270, filed Dec. 14, 1925, means are provided for suitably insulating the leer in order to maintain a more uniform temperature transversely therein. In conjunction with this feature it is the fundamental purpose of the present invention to create and maintain longitudinally of the leer and around the glass sheet passing therethrough a condition which is capable of protecting the sheet from any fluctuating temperatures which might interfere with the proper annealing of the glass.

The leer improvements covered by this invention are not necessarily limited to the sheet glass apparatus illustrated in the drawing, but are applicable to most any type of annealing leer.

A preferable leer construction for the purpose of meeting the requirements of the present invention is shown in the accompanying drawings. The side walls 11 of the leer are provided with a plurality of vents 12 having flues 13 communicating therewith. The effectiveness of the flues 13 is controlled by dampers 14 provided therein. It will be noticed that the vents 12 are spaced longitudinally of the leer at spaced intervals and that their vertical distances from the line of travel of the sheet gradually decreases until the last few are approximately in line with the sheet. The ceiling at the end of the leer beyond the side wall vents 12 is provided with a plurality of vents 15. These vents are arranged in staggered groups in open communication with conduits 16 and 17, also in the leer ceiling, each conduit leading to its respective flue 18 or 19. Dampers 20 are provided within the flues 18 and 19 for controlling the draft created by them.

It is believed that with a leer constructed in accordance with the present invention, a very satisfactory annealing condition can be attained. It is a well-known fact in the art

of forming sheet glass that the annealing thereof is quite an important factor, so the least the annealing atmosphere or medium through which the glass passes is disturbed and the more gradual the temperature of the annealing atmosphere is reduced, the more satisfactory the final results will be.

It will be possible in the leer constructed in accordance with the present invention to

10 surround the glass sheet with a sustained annealing medium whose temperature and pressure is comparatively high at one end of the leer and which gradually approaches atmospheric temperature and pressure at the other 15 end of the leer. This medium is continuously maintained by withdrawing heat from the leer at different levels through the side wall vents 12. The amount of heat withdrawn at different points along the leer is 20 controlled by the use of the dampers 14 in the flues 13. In order that the glass sheet may gradually be subjected to atmospheric pressure and temperature, (there being a pressure greater than atmospheric pressure 25 in the leer due to the presence of the high temperatures therein) the medium surrounding the glass gradually vanishes by being gradually drawn through the vents 15 in the far end of the leer ceiling. The rapidity with 30 which the medium is caused to vanish is controlled by the use of the dampers 20.

The glass sheet during its advancement through the annealing medium whose temperature has been gradually and systematically reduced, it is to be understood, has also been protected from stray fluctuating temperatures which prevail within the ordinary leer, these fluctuating temperatures often causing considerable breakage.

40 In the ordinary annealing leer the temperature therein is reduced by gradually reducing the number of burners in the leer and, also by reducing the gas supply to the burners at the colder portion of the leer. The gases 45 and heat are removed from this type of leer through a single flue usually placed somewhere along the leer ceiling. The draft created by this flue it is apparent causes a very undesirable condition in the leer, creating a plurality of air currents of varying 50 temperatures to sweep from all directions toward the flue across the glass sheet.

The improvements covered by the present invention eliminate the objectionable features 55 of a single ceiling flue, for as the temperature of the annealing medium is lowered, gases and heat pass from the leer at a plurality of points corresponding to the location of each reduction in temperature of said medium.

Another advantage of the present invention resides in the fact that the leer rolls which are enclosed within the above-mentioned medium therefore will have approximately the 60 same temperature as said medium, and thus

they will have little or no effect toward varying the temperature of the glass as it engages their peripheries.

It is believed that by annealing glass by the improved process covered by this invention, greater production will be attained, and the glass having been better annealed will be less subject to fracture or breakage when in commercial use.

Claims:

1. In a leer for annealing and cooling a continuous glass sheet, roller means for moving the sheet therethrough, means for releasing supplemental heat into the atmosphere along a portion of the leer, sealing means for preventing draft currents of local character at the level of sheet, and means for causing local escape movement of heated atmosphere at different levels below the sheet. 75

2. In a leer for annealing and cooling a continuous glass sheet, roller means for moving the sheet therethrough, means for releasing supplemental heat into the atmosphere along a portion of the leer, sealing means for preventing draft currents of local character at the transit level of sheet, and means for causing local escape movement of heated atmosphere at different levels below the sheet in that portion of leer where heat is released, and for drawing off the heated atmosphere at the series of exits checkerboarded above the level of sheet at the cooling end of leer. 85

3. A sheet glass annealing oven for receiving a horizontally moving sheet, including side walls and a ceiling, said walls being provided at longitudinally spaced locations with vents arranged in different horizontal planes beneath the sheet. 90

4. A sheet glass annealing oven for receiving a horizontally moving sheet, including side walls and a ceiling, said walls being provided at longitudinally spaced locations with vents arranged in different horizontal planes beneath the sheet, the vertical distances from the vents to the line of travel of the sheet gradually decreasing from the hot to the cold end of the oven. 105

5. A sheet glass annealing oven for receiving a horizontally moving sheet, including side walls and a ceiling, said side walls being provided at longitudinally spaced locations with vents arranged in different horizontal planes beneath the sheet, and dampers for controlling said vents. 110

6. A sheet glass annealing oven for receiving a horizontally moving sheet, including side walls and a ceiling, said side walls being provided at longitudinally spaced locations with vents arranged in different horizontal planes beneath the sheet, and the ceiling being also provided with a plurality of vents at the end of the oven beyond the side wall vents. 120

7. A sheet glass annealing oven for receiving a horizontally moving sheet, including side walls and a ceiling, said side walls being 125

- provided at longitudinally spaced locations with vents arranged in different horizontal planes beneath the sheet, the vertical distances from the vents to the line of travel of the sheet gradually decreasing from the hot to the cold end of the oven, and the ceiling being also provided with a plurality of vents at the cold end of the oven beyond the side wall vents. 5
8. In a sheet glass annealing oven, means for supporting the sheet horizontally, means within the oven for heating the same, and means in the side walls of the oven at different horizontal planes beneath the sheet for withdrawing heat therefrom. 10
9. In a sheet glass annealing oven, means for supporting the sheet horizontally, means for introducing heat within the oven at spaced locations longitudinally thereof, and means in the side walls of the oven at different horizontal planes beneath the sheet for withdrawing heat therefrom, the vertical distances from the last named means to the line of travel of the sheet gradually decreasing from the hot to the cold end of the oven. 15
10. In a sheet glass annealing oven, means for supporting the sheet horizontally therein, means for introducing heat within the oven at spaced locations longitudinally thereof, means in the side walls of the oven at different horizontal planes beneath the sheet for withdrawing heat therefrom, and means in the ceiling of the oven at one end thereof beyond the second named means for also withdrawing heat therefrom. 20
11. The process of annealing sheet glass which consists in passing the sheet longitudinally through a confined heated atmosphere, and gradually decreasing the temperature of the sheet by drawing off heat at spaced intervals and at different horizontal levels beneath said sheet. 25
12. The process of annealing sheet glass which consists in passing the sheet horizontally through an annealing oven, introducing heat into the oven at spaced locations longitudinally thereof, and gradually decreasing the temperature of the sheet by drawing off heat at spaced intervals and at different horizontal levels beneath the sheet and in also drawing off heat from above the sheet. 30
13. The process of annealing sheet glass which consists in passing the sheet through a confined heated atmosphere, and gradually decreasing the temperature of the sheet by drawing off heat at spaced intervals and at different horizontal levels. 35
14. The process of annealing sheet glass which consists in passing the sheet in a generally horizontal direction through a confined heated atmosphere, and gradually decreasing the temperature of the sheet by drawing off heat at spaced intervals and at different horizontal levels. 40
15. In a sheet glass annealing oven, means for supporting the sheet therein, means for heating said oven, and means in the side walls of the oven arranged in different horizontal planes for withdrawing heat therefrom. 45
16. A sheet glass annealing oven for receiving a substantially horizontally moving sheet including a bottom, side walls, and a ceiling, said side walls being provided at longitudinally spaced locations with vents arranged in different horizontal planes. 50
17. A sheet glass annealing oven for receiving a substantially horizontally moving sheet including a bottom, side walls, and a ceiling, said side walls being provided at longitudinally spaced locations with vents arranged in different horizontal planes, and the ceiling being also provided with a plurality of vents at the end of the oven beyond the side wall vents. 55
